UNITED STATES PATENT OFFICE

ELIZABETH MACLACHLAN, OF ELKHART, INDIANA, ASSIGNOR TO WILLIAM S. FERRIS,
OF ELKHART, INDIANA.

CUTTING AND CLEANING TOOL.

1,289,201.

Specification of Letters Patent. Patented Sept. 4, 1917.

Application filed October 14, 1916. Serial No. 125,687.

To all whom it may concern:

Be it known that I, ELIZABETH MACLACHLAN, a citizen of the United States, residing at Elkhart, in the county of Elkhart and State of Indiana, have invented certain new and useful Improvements in Cutting and Cleaning Tools, of which the following is a specification.

My invention relates to cutting, cleaning, and excavating tools of the type shown in United States Patent, No. 774,142 of November 1, 1904 to Charles Brick. In the operation of tools of this character the spring jaws are alternately opened and sprung together thousands upon thousands of times being closed to grip the dirt and being opened to release same.

The general object of my invention is to provide a device of this character which shall be of simpler construction; which shall be of less cost; which shall be lighter; which shall be of such construction that the deforming tendency of the action of moving the spring jaws together shall be minimized; and which shall more surely automatically release the material gripped therein.

My invention consists generally in the form, arrangement, construction and coöperation of parts whereby the above named objects, together with others which will appear hereinafter, are attainable, and my invention will be more readily understood by reference to the accompanying drawings which illustrate the preferred construction thereof.

In the said drawings, Figure 1, is a perspective view of a device embodying my invention with an intermediate portion broken away.

Fig. 2— is an enlarged central vertical section with the intermediate portion broken away and showing the jaws in open position.

Fig. 3— is a view similar to Fig. 2, but with the spring jaws drawn together; and

Fig. 4— is a detail view of the spring jaw roller and associated parts.

In the drawings, 10, indicates a tubular body provided at its lower end with a U-shaped head portion 11, having slightly outwardly extending channel shaped portions 12—12. At the opposite end, the body 10, is provided with a slotted head 13, and to the upper end of the head 13, a cross arm 14, is secured.

Extending through the slot of the head 13, is another cross arm, 15, similar to the cross arm 14, and secured to this cross arm 15, is a rod 16, which extends down through the body 10, and into the space between the fingers 12—12 of the head 11. To the lower end of the rod 16, I attach a U-shaped clip 20, having depending spaced fingers 21. The fingers 21, are provided with alined holes 22, through which a bolt 23, passes. The bolt 23, serves to support and hold a roller or cylinder 25, which has a central opening to receive the bolt and which is of length substantially equal to the distance between the spaced fingers 21. The roller or cylinder 25, is of such size and is so spaced relative to the upper portion of the U-clip 20, as to provide a space 26, therebetween. The dirt or weed gripping and holding portion of the implement, comprises a strip of spring material which I bend to form a gently curving or arcuated upper portion 30, with oppositely and outwardly extending substantially straight portions 31 and 32, and inwardly extending end portions 33 and 34. It will be understood that if the instrument is to be used for cutting weeds or removing dirt, the jaws are placed in desired position and in open condition and pressed into the material whereupon the operator draws the handle 15, to the handle 14, thus closing the jaws as shown in Fig. 3. Upon releasing the handle, the jaws are automatically opened to discharge the material carried thereby. In devices hitherto devised, the spring jaws have soon lost their elasticity with the result that they do not automatically discharge the material and furthermore, in devices hitherto devised, it has also been necessary to provide a spring to return the handle and rod to open position. I eliminate these objections and greatly simplify the device by the novel construction of the spring jaw and the means for drawing it together and opening it.

To this end, I provide the roller or cylinder 25, and I make the radius of the roller smaller than the radius of the spring portion 30. In this way, the spring arcuate 30, bears substantially along a line and as the handles are moved together, to close the fingers 31 and 32, the curved portion 30, can freely change its position, form, or curvature without the slightest danger of being moved beyond its elastic limit or of being

sheared or abruptly bent by contact with a sharp edge or abutment. In other words, a portion of the arcuate portion 30, can wrap itself around the roller or cylinder due to the free intervening spaces 35. By gently curving the portion 30, a strong spring metal may be used and still be freely moved together by contact of the portions 31 and 32, with the lower ends of the channel 10 shaped fingers 12-12. Also because of this construction, I am able to dispense with the additional spring hitherto employed to return the handle 15, and operating rod 16, to open position. Furthermore, because the 15 spring jaws are never abruptly bent, kinked or moved beyond their elastic limit they always open automatically to discharge the material and to return to normal position when the pressure on handle 15, is released.

20. I claim:

1. In a tool of the class described, the combination of a main hollow body having a pair of fingers, a rod movable through the body, a spring jaw strip, associated with 25 said body fingers and having a curved portion, means carried by said rod engaging the curved portion of said spring jaw strip, said means being curved and of lesser radius than the curved portion of the spring jaw 30 strip.

2. In a tool of the class described, the combination of a main hollow body having a pair of fingers, a rod movable through said body, a U-shaped clip secured to the 35 end of said rod, an arcuate bearing face supported in and spaced from the upper portion of the U-clip and a spring jaw strip having a curved upper portion, passing through the space between said arcuate face 40 end, and the upper portion of said clip, said curved portion having a greater radius than the curved portion of the arcuate bearing face and the said spring jaw strip having outwardly disposed substantially straight 45 portions in engagement with the fingers carried by the body, whereby movement of the clip toward the body causes the spring jaw strip fingers to move together and whereby when released, the outward pressure of the 50 spring jaw strip serves to return the rod

and handle to normal position and automatically to discharge any material carried by the spring jaw strip.

3. In a tool of the class described, the combination of a main body having a pair 55 of fingers at one end, a rod, longitudinally movable between said fingers, a U-shaped clip carried by the rod and normally spaced from the juncture of said fingers with the body, a cylinder carried by said U-shaped 60 clip and having its upper portions spaced from the body part of the U-clip, and a spring jaw strip having a curved upper portion passing through the space between said cylinder and U-clip, said cylinder 65 engaging the spring jaw strip and causing the fingers thereof to move together when the said rod is moved and the jaw strip serving to return the parts to normal position and automatically to discharge any material 70 gripped thereby.

4. In a tool of the class described, the combination of a hollow body portion having a pair of fingers, of a rod movable through the body, a spring jaw strip associated 75 with said body fingers and having a curved portion, a cylinder carried by said rod engaging the curved portion of the spring jaw strip and serving to support it, said cylinder being of lesser radius than the 80 curved portion of the spring jaw strip.

5. In a tool of the class described, the combination of a hollow body, having a pair 85 of fingers, a rod movable through the body, a spring jaw strip associated with said body fingers and having a curved portion, a U-clip carried by said rod, a bolt carried in the U-clip and having a hollow cylinder mounted thereon, said cylinder engaging the curved portion of the spring jaw strip and 90 having a radius less than the radius of the curved portion of the jaw strip.

In testimony thereof, I have hereunto set my hand, this 11th day of Oct., 1916, in the presence of two subscribing witnesses.

ELIZABETH MacLACHLAN.
